Patented May 11, 1915.

UNITED STATES PATENT OFFICE.

JOHN L. CLARK, JR., OF FAIRHAVEN, MASSACHUSETTS.

NECKTIE.

1,139,016.

Specification of Letters Patent. Patented May 11, 1915.

Application filed November 30, 1914. Serial No. 874,768.

To all whom it may concern:

Be it known that I, JOHN L. CLARK, Jr., of Fairhaven, in the county of Bristol and State of Massachusetts, have invented certain new and useful Improvements in Neckties; and I do hereby declare the following to be a full, clear, and exact description of the invention, such as will enable others skilled in the art to which it appertains to make and use the same.

This invention relates to improvements in neckwear, and more particularly to that class of neckwear generally designated as ties.

It is one of the objects of this invention to suitably reinforce those ties which are formed of blanks cut to the proper shape and then folded over to form a complete tie.

A further object consists in reinforcing the tie in such a manner as to prevent longitudinal and lateral distortion of the tie during the tying operation, or when adjusting the tie between folds of the collar.

A still further object consists in the provision, on the neck portion and knotting portion of the tie, of a "slip-easy" surface which will admit of the tie being pulled or adjusted, when inserted between the folds of the collar, with a minimum of friction and will also enable the wearer to tie and untie the knot without difficulty. And still another object of this invention is to reinforce the body of the tie throughout its length and width and to have the reinforcing member form the "slip-easy" surface of the neck and knotting portions of the tie.

Other features of the invention will be more fully described in connection with the accompanying drawing forming a part of this specification, and will be more particularly pointed out in and by the appended claims.

In the drawing:—Figure 1 is a view, in perspective, of a tie made up according to one form of my invention and having open ended flaps. Fig. 2 is a perspective view of one flap of the tie shown in Fig. 1 with the fold thereof opened out to show the reinforcing strip. Fig. 3 is a sectional view on the line 3—3 of Fig. 1. Fig. 4 is a sectional view on the line 4—4 of Fig. 1. Fig. 5 is a sectional view on the line 5—5 of Fig. 1 and showing the body, forming the facing of the tie, and the reinforcing strip or backing secured thereto. Fig. 6 is an enlarged view showing one corner of Fig. 5.

Like characters of reference designate similar parts throughout the different figures of the drawing.

The invention, as shown in the drawings, is an open-end necktie with the goods forming the body portion cut on the bias, and it is this type of neck tie which it is most preferable to reinforce according to my invention, since a necktie in which the goods forming the body portion is cut on the bias is extremely liable to become laterally and longitudinally distorted through pulling the same in adjusting it between the folds of a collar.

The necktie shown comprises a body 1, forming a facing, and a substantially inextensible satin finished reinforcing backing strip 2. The body 1 is folded over at the ends to form the open ended flaps 3 and 4, provided with shoulders 5 and 6 respectively. The reinforcing backing strip 2 extends from side to side of each of the flaps 3 and 4, as best shown in Fig. 2 of the drawing, and is stitched or otherwise tacked to

the margins of the flaps to reinforce the same against lateral distortion. Also the reinforcing backing strip 2 extends throughout the length of the tie body 1 in blank and is stitched or otherwise secured to the end edges thereof, thereby preventing longitudinal distortion of the tie, during the tying or adjusting operation.

From the shoulder 5 to the shoulder 6, which includes the neck portion 7, the body 1 is only of sufficient width to form the facing of the tie and neck portion, and the satin finish reinforcing

backing strip 2 forms a back for the neck portion, which thereby provides, by reason of its satin finish, a "slip-easy" length which is adapted to lie between the folds of the collar when the tie is in position, and which allows the neck portion of the tie to

slip easily when the ends of the tie are pulled, thus facilitating adjustment of the tie and reducing very materially the strains which must be exerted on the tie by the wearer during the tying operation. The satin finish reinforcing backing strip 2 ex-

extends, as before stated, from side to side of each of the flaps, and also extends throughout the length of the tie. However at the shoulders 5 and 6 the reinforcing strip is disposed between the facing and the over-

turned portions of the flaps thus placing it between the shoulders and the facing. From shoulder to shoulder the reinforcing backing

strip is stitched or otherwise secured along its marginal edges to the facing, and at the shoulders it is also secured to the facing, the lines of stitching adjacent the shoulder and securing the backing strip to the body forming the facing converge and meet at the shoulders.

In the neck portion 7 of the tie, the usual interliner 8 is disposed, and lies between the 10 satin finish reinforcing backing strip 2 and the body forming the facing of the neck portion 7. It is preferable, at the neck portion 7 to run several lines of stitching 9 which strengthen the neck portion 7.

15 It will be seen from the foregoing description that I have provided, in a necktie, a reinforcing strip having a satin finish which provides a "slip-easy" length at the neck and also reinforces the tie from end 20 to end and side to side, and while I have herein shown and described one specific form of my invention, I do not wish to be limited thereto except for such limitations as the claims may enforce. It is also to be noted that my invention is applicable to 25 neckties which are not cut on the bias. Furthermore it is to be noted that my invention may be embodied in ties of both the four-in-hand and bow style without departing from 30 the spirit of the invention.

I claim:

1. In a necktie, a tie body including a

neck portion and open ended flaps provided with shoulders, that portion of the tie body constituting the neck portion being only of 35 sufficient width to form the facing of the neck portion, a satin finish reinforcing strip co-extensive with the body in blank and tacked to the margins of the neck portion and forming a "slip-easy" backing therefor, 40 said strip extending beyond the shoulders of the flaps and tacked to the shoulders and to the margins of the flaps, substantially as described.

2. A necktie consisting of a tie body comprising a neck-band portion and open end tying flaps, and a substantially inextensible reinforcing backing co-extensive with the tie body in blank and tacked to the margins thereof. 45

3. An open end necktie consisting of a tie body comprising a neck-band portion and open end tying flaps, and an inextensible backing for the neck-band portion and said tying flaps, said backing being co-extensive with the tying flaps in blank and tacked to the margins of said flaps. 50 55

In testimony whereof, I have signed this specification in the presence of two subscribing witnesses.
